UNITED STATES PATENT OFFICE.

CHARLES F. MEILINK, OF TOLEDO, OHIO.

FILING-CASE.

1,184,978.

Specification of Letters Patent. Patented May 30, 1916.

Application filed November 16, 1914. Serial No. 872,291.

To all whom it may concern:

Be it known that I, CHARLES F. MEILINK, a citizen of the United States of America, residing at Toledo, Lucas county, Ohio, 5 have invented new and useful Filing-Cases, of which the following is a specification.

This invention relates to guides or carriers for relatively reciprocable members.

This invention has utility when incorporated 10 as a support or extension guide for drawers, as vertical file drawers in metal furniture.

Referring to the drawings: Figure 1 is a perspective view of an embodiment of the 15 invention in a minimum size or single drawer vertical file unit, with the drawer closed or housed in the case; Fig. 2 is a side elevation, with parts broken away, showing the drawer open, or at its outward limit 20 of travel; Fig. 3 is a fragmentary detail, on an enlarged scale, on the line III—III, Fig. 1, looking in the direction of the arrow; Fig. 4 is a view on the line IV—IV, Fig. 1, on an enlarged scale looking in the 25 direction of the arrow, and Fig. 5 is a sectional view on the line V—V, Fig. 1, looking in the direction of the arrow.

The case comprises the top wall 1, the side walls 2, the back wall 3, and the bottom wall or side 4. This rectangular case 30 has vertically disposed stiffening angles 6 in each corner thereof, providing in this otherwise skeleton structure considerable rigidity.

Disposed along each side of the case is a track carrier member having the upper portion 7 contacting the case side 2 above the carrier member channel portion 8, downward from which channel portion 8 extends 40 the case side contacting portion 9 to the flanged portion 10 of the carrier member contacting the bottom side 4 of the case. These members may be mounted fixedly in the case or housing by the electric spot weldings 11 therealong, and similar weldings 11 45 may serve to unite the case sides and angles in the assembled structure.

The case or fixed track 12 may be firmly attached to the case by the screws 13 mounting this track member 12 on the channel track carrier member.

Movable in and out relatively to the case or supporting member is the drawer or member to be carried 14, having along its 55 sides the channels 15. Adjacent this chan-

nel section 15 on each side of the drawer 14 are the tracks 16, fixedly mounted in position thereon by the screws 13 to hold a pair of tracks 16 in a plane with an intermediate track 12. Disposed out of the plane 60 of these tracks groups of threes, are the traveling guides 17. The guide 17 has centrally thereof the pair of opposing grooved traction rollers 18 contacting two of the four trackways provided by the three tracks 65 12, 16, and but slightly clearing the other two of said ways, so that as the position of the drawer as to the case changes these rollers 18 may have tractive action on any two of the four trackways. 70

Near the upper forward end of the guide 17 is a third traction roller 18, grooved, and a fourth such roller 18 near the after lower portion of the guide. The forward lower portion of the guide 17 carries the 75 grooved guide roller 19, while the after upper portion of the guide 17 carries a second guide roller 19. These guide rollers 19 normally function only as guides by having their flanges coact with the tracks 80 to maintain the members in proper relative alinement, but in lifting the forward end of the drawer, these guide rollers 19 may then additionally serve as anti-friction devices. The guide 17 is the carrier for the 85 grooved rollers which provide the anti-friction extension travel for the drawer as to the case.

The detachable independent tracks are of finished rigid material which may be installed 90 after the case and drawer are completed through the coatings, enameling and baking processes. The trackways are accordingly clean and there is no occasion in the normal finishing of the case before installation of the track ways to exercise care in omitting to coat any portion, so dipping may occur if desired. The trackways may accordingly be accurately alined upon assembling, thereby insuring a nicety of positioning for continued easy operation throughout the entire life of the structure. There is thus no occasion for binding and incidental rough usage in operation, and the device is 95 a permanent utility. 100

The location of the tracks at stiffened points provides ample strength for carrying loads greatly in excess of any normally required for the structures. The drawer channel 15 makes the drawer sides stiff at the 110

loaded points carrying the tracks 16. The carrier member channel 8 makes the case stiff not only along the sides 2, but in the unit structure of the carrier member extending to the second case side 4, there is distribution of load to this second side 4 as well as incidental stiffening of the side 2 against any weaving or warping.

To limit the relative travel of the drawer 10 as to the case the gravity dog 20 is disposed to ride along the upper way of the track 12 to fall into the under cut notch 21 thereby holding the guide 17 from further travel out of the case, while the dog 22 riding upon the 15 upper trackway of the lower track 16 enters the under cut notch 23 to hold the drawer from further outward withdrawal as to the guide 17. These gravity dogs are carried by the guide, and as the drawer is moved inward, the dogs ride out of the under cut notches.

What is claimed and it is desired to secure by Letters Patent is:

1. A casing member, a drawer member, 25 one of said members having a channel providing opposing tracks, and the other member having a track extending between the opposing tracks of the channel, a guide movable relatively to the members, and means 30 including rollers on the guide interposed between the tracks for moving the guide out of the casing to a determined position for sustaining the drawer in extended position.

2. A casing member having extending 35 therefrom means providing a track, a drawer member providing a pair of embracing tracks, a guide movable relatively to the members, and means including rollers on the 40 guide interposed between the tracks for moving the guide out of the casing to a deter-

mined position for sustaining the drawer in extended position.

3. A casing member, a drawer member, one of said members having a track providing channel, and the other member having a track extending into the channel, a guide disposed in said channel movable relatively to the members, and means including rollers on the guide coacting with the tracks for moving the guide out of the casing to a 45 determined position for sustaining the drawer in extended position.

4. A drawer member having a channel providing opposing tracks, a casing member having extending therefrom means providing a track extending between the opposing tracks of the channel, a guide movable relatively to the members and disposed in said channel, and means including rollers on the 50 guide interposed between the tracks for moving the guide out of the casing to a determined position for sustaining the drawer in extended position.

5. A casing member, a drawer member, one of said members providing opposing 55 tracks and the other member having a track extending between the opposing tracks, a guide movable relatively to the members, rollers on the guide interposed between the tracks, and means for limiting the travel of 60 the guide out of the casing to a determined position for sustaining the drawer in extended position including dogs disposed adjacent said tracks.

In witness whereof I affix my signature 75 in the presence of two witnesses.

CHARLES F. MEILINK.
